BOOM CLAMP

Noble R. Beale, Berkeley, Calif.

Application November 24, 1950, Serial No. 197,315

6 Claims. (Cl. 248—309)

This invention relates to a new and improved boom clamp for securing a ship's cargo boom during times when the boom is not in use, such as when the ship is underway.

The particular embodiment of the invention which is illustrated in the drawings and which will be described hereinafter in greater detail comprises, generally, a frame adapted to be rigidly secured to a stationary part of a ship (such as a ship's mast) on which is mounted pivotally a pair of clamping jaws movable pivotally to open and closed positions. Means is provided to maintain the jaws in normally open position, and the arrangement is such that when the jaws are open, the inner ends thereof establish cam surfaces against which inwardly directed force, such as may occur upon a boom being moved against the jaws, will cam the jaws closed around the boom. The device incorporates also a locking mechanism which is adapted to lock automatically the jaws in closed position when the latter have closed about a boom to be secured. Means associated with the locking mechanism is provided to permit said mechanism to be operated at a location remote from the boom clamp mechanism per se, thereby rendering it unnecessary for any of the ship's crew to be in the immediate vicinity of the boom clamp during either boom clamping or unclamping operations.

A principal object, therefore, of the present invention is to provide a mechanism which is adapted to automatically clamp against and secure a ship's cargo boom or the like without requiring the services of any of the ship's personnel within the immediate vicinity of the boom clamp. Thus, if a boom is to be secured to the upper portion of a ship's mast (where the device may be located), it is unnecessary for any of the ship's crew to climb aloft to accomplish this end.

A further object of the present invention is to provide a boom clamp of the type briefly mentioned hereinabove which permits release of a secured boom from a point remote from the boom clamp itself. Again, the usual necessity for ship personnel to climb aloft to unlash a boom from secured position is avoided.

Another object of the present invention is to provide an automatic boom clamp incorporating novel guide means to assist in guiding a boom into securing position within the clamping jaws of the device.

Other objects of the present invention will become apparent upon reading the following specification and referring to the accompanying drawings in which similar characters of reference represent corresponding parts in each of the several views.

In the drawings:

Fig. 1 is a perspective view of the device partly in section and with some of the parts shown fragmentarily.

Fig. 2 is a side elevational view of the device.

Fig. 3 is an end elevational view of the device.

Fig. 4 is a generally schematic view of the device showing the operation of the clamping jaws in relation to the locking mechanism.

Fig. 5 is a fragmentary view showing the device secured to a ship's mast adjacent the upper end thereof.

Referring now more particularly to the drawings, the present invention comprises generally a frame A supporting a pair of similarly formed clamping jaws B and a jaw locking mechanism C.

Frame A comprises, more specifically a pair of spaced oppositely facing parallel plates 11 and 12 secured to one another by a number of spacing bars or bolts, such

2

as indicated at 13. The upper end of frame A terminates in a pair of outwardly diverging guide arms 14, and preferably a plurality of angle bars, such as indicated at 16, are secured to opposite sides of arms 14 and project outwardly therefrom to form, in effect, a continuation of said guide arms for facilitating the guiding of a boom into proper location within the clamping jaws B, as will appear more fully hereinafter.

Each of the clamping jaws is identically formed and comprises a somewhat triangular-shaped plate 17 provided with a semi-circular clamping shoe 18. Each jaw is mounted pivotally intermediate its outer end 19 and inner end 21 by a pivot pin 22 which projects through openings formed in plates 11 and 12 and is supported thereby. From the foregoing it is seen that the jaws are movable pivotally from a closed position, as indicated in Figs. 1 and 2, to an open position such as illustrated in Fig. 4.

Means, comprising expansion springs 23, are provided to normally urge the jaws to open position. More specifically, each spring 23 is attached at one of its ends to an associated aperture 13a formed in opposite sides of plate 11, and to outer end 19 of an associated clamping jaw, as indicated at 24. The jaw springs thus tend to normally spread the outer ends of the jaws apart from one another which, in turn, correspondingly tends to move the inner ends of the jaws toward one another as indicated in Fig. 4.

The locking mechanism heretofore designated generally at C is adapted to lock automatically the clamping jaws in closed position. More specifically, the locking mechanism comprises cam shaft 26 supported rotatably in suitable bearings 27, and is provided with an outwardly projecting control lever 28, keyed or otherwise rigidly secured to said shaft, and to which a lanyard or control wire 40 may be attached. A pair of upwardly projecting bifurcated cams 29 are mounted rigidly on shaft 26 and are adapted for rotation therewith.

Associated with each cam 29 is a stud pin 31 provided with a nut or enlarged head 32. Each stud pin is mounted slidably in a bearing or bracket 33 and the inner end of each pin projects slidably through an opening formed in plate 11 for registry and locking engagement with an aperture 34 formed adjacent inner end 21 of an associated clamping jaw B. A coil spring 36 is mounted on each pin with its opposite ends bearing against the enlarged shoulder portion 37 of said pin and against the inner face of the associated pin supporting bracket 33 and functions to normally urge said

pin inwardly into engagement with its associated clamping jaw. Each bifurcated cam 29 straddles an associated pin with its cam faces 35 engaging the inner surfaces of enlarged head or nut 32 with which said cam is respectively associated. Movement of lever 28 in the direction of arrow D will rotate cam shaft 26 in a direction appropriate to cause cams 29 to swing outwardly and cam stud pins 31 slidably outwardly in their bearings against the spring forces of springs 36. As soon as the locking pins have been cammed out of engagement with their respectively associated apertures 34, jaw springs 23 will, of course, cause the jaws to open. During opening or closing movements of the jaws, the inner ends 38 of stud pins 31 will ride freely over and in sliding contact with triangular plate portions 17 of the jaws without interfering with or hindering the action of said jaws. Only when the jaws have been moved to closed position will apertures 34 be moved into registry with the locking pins, at which time the said pins will by virtue of springs 36 acting thereagainst, automatically project into said apertures to lock the jaws in closed position as aforesaid.

Referring now particularly to Fig. 4, it is seen that when the jaws are in fully open position, the inner ends thereof establish suitable cam surfaces 39 against which a cargo boom, such as indicated at 41, can bear to cause said jaws to close against the pressure of springs 23. The outwardly diverging guide arms, comprising angle bars 16 facilitate guiding of the cargo boom into position within the open clamping jaws.

Fig. 5 illustrates how a boom clamp embodying the present invention may be secured to a ship's mast ad-

adjacent the top thereof, as indicated at 50, in order to permit securing of a cargo boom 41a adjacent and parallel to said mast and well out of the way of normal ship traffic and ship operations. Fig. 5 also illustrates how lanyard 40, heretofore mentioned, may be run from the control lever of the boom clamp downwardly to the base of the mast, for example, from which location the locking mechanism of the device may be controlled. It will be recalled that the locking of the boom within the clamping jaws is automatic upon the boom being moved by its winch into position within and against the jaws, and that opening of the jaws is automatic upon actuation of the control lever to cause the spring biased stud pins to be withdrawn from engagement with the jaws. In view of the fact that this latter operation is the only one requiring manual control, and further in view of the fact that this control may be effected through simple manipulation of a lanyard or other similar suitable remote control means, it becomes unnecessary for any member of the ship's crew to climb aloft so as to be within the near vicinity of the device during any of its operations.

From the foregoing it is seen that a boom clamp embodying the present invention may be installed on practically any type of ship. The device may be welded, bolted, or otherwise firmly secured to a ship's mast, as previously suggested, and in this connection, the frame of the device may be formed with a suitable cut-out (indicated fragmentarily at 52) proportioned to engage said mast to facilitate the welding or bolting of the device to said mast. It is also believed evident that the present boom clamp may be secured to a stationary part of a ship other than a ship's mast, as for example, the boom clamp may be anchored to the deck of the ship in order to permit a cargo boom to be cradled and secured in horizontal position if so desired.

Although the present invention has been described in some detail by way of illustration and example for purposes of clarity of understanding, it is understood that certain changes and modifications may be practiced within the spirit of the invention and scope of the appended claims.

I claim:

1. A boom clamp comprising a frame, a pair of coacting clamping jaws each having a substantially semi-circular boom clamping shoe, each jaw independently pivotally mounted intermediate its ends to said frame, said jaws movable pivotally from a closed position to an open position whereat the outer ends of said jaws spread apart from one another and the inner ends of said jaws move toward one another, means to maintain said jaws in normally open position, releasable interlocking elements for locking said jaws in closed position, said interlocking elements comprising a pair of stud pins slidable in bearings mounted on said frame and each respectively engageable in a registering aperture formed in an associated jaw when said jaw has moved to closed position, jaw when said jaw has been moved to closed position, means to axially withdraw said stud pins from said apertures to permit opening of said jaws, the inner ends of said jaws presenting cam surfaces against which inwardly directed force will cause said inner jaw ends to spread and the jaws to move into closed position, and means comprising a pair of stationary guide arms mounted to

said frame projecting divergently outwardly from said clamping jaws for defining a V-shaped guideway for guiding a boom into position within said jaws.

2. A boom clamp according to claim 1 and wherein spring elements are provided to normally spring bias said stud pins toward said associated jaws whereby said pins automatically engage said respectively associated apertures when said jaws are closed and said apertures have moved into registry with said pins.

10 3. A boom clamp according to claim 1 and wherein said means to withdraw said stud pins from said apertures include cams engageable with said pins.

4. A boom clamp according to claim 1 and wherein said means to maintain said jaws in normally open position comprises spring elements connected to said jaws exerting a spring force appropriate to normally urge said jaws to open position.

5. A boom clamp comprising; a frame including a pair of oppositely facing frame plates secured together in parallel spaced relationship by spacing bars, a pair of coacting substantially semi-circular clamping jaws each individually pivotally mounted intermediate its ends to said frame between said frame plates, said jaws movable pivotally from a closed position to an open position

25 whereat the outer ends of said jaws spread and the inner ends of said jaws close toward one another, spring elements connected to said jaws and said frame respectively to normally urge said jaws to said open position, releasable interlocking elements for locking said jaws in closed position comprising a pair of stud pins slidable axially in bearings mounted on said frame and each respectively engageable in a registering aperture formed in an associated jaw when said jaw has moved to closed position, a cam shaft mounted rotatably on said frame

30 supporting a pair of cams each having a cam surface engageable with a portion of an associated pin, said cams arranged to cam said pins outwardly slidably in their said bearings upon actuation of said cam shaft to cause axial withdrawal of said pins from their respectively associated jaw apertures whereupon said jaw springs will urge said jaws to open position, the inner ends of said jaws presenting cam surfaces against which inwardly directed force will cause the inner jaw ends to spread and the jaws to move into closed position, and means comprising a pair of stationary guide arms mounted to said frame projecting divergently outwardly from said clamping jaws for defining a V-shaped guideway for guiding a boom into position within said jaws.

6. A boom clamp according to claim 5 and wherein a control lever is provided on said cam shaft for actuating said cam shaft, and wherein a lanyard attachable to said control lever is provided to permit actuation of said cam shaft via said lanyard from a location remote from said boom clamp.
